UNITED STATES PATENT OFFICE.

JOHN ROBERT HARRISON, OF BALLARAT, VICTORIA, AUSTRALIA, ASSIGNOR OF ONE-HALF
TO HUGH VICTOR MCKAY, OF MELBOURNE, AUSTRALIA.

AMALGAMATOR AND CONCENTRATOR FOR ORES AND TAILINGS.

No. 909,293.

Specification of Letters Patent.

Patented Jan. 12, 1909.

Application filed May 9, 1906. Serial No. 315,965.

To all whom it may concern:

Be it known that I, JOHN ROBERT HARRISON, a subject of the King of Great Britain and Ireland, residing at No. 47 Albert street, 5 Ballarat, in the British State of Victoria, Australia, iron founder, have invented an Improved Amalgamator and Concentrator for Ores and Tailings, of which the following is a specification.

10 This invention relates to an improved amalgamator and concentrator for ores and tailings.

It consists of a table or annular pan, whose 15 surface is of a tapering volute form in plan, provided with an internal gutter or race to receive and carry off the gangue. The said table surface is slightly inclined downwards transversely from its inner edge to its outer rim or periphery and also inclines downwards 20 circumferentially from its feed end to its discharge end, further the table is suspended from overhead supports and has a gyratory or eccentric shaking motion imparted to it by a horizontal eccentric which works in a 25 boss at the center of pan arms, also for some classes of ore and especially rich ore two or more pans may be supported one above the other.

The invention will now be fully described 30 aided by a reference to the accompanying sheet of drawings in which:—

Figure 1 shows a sectional elevation of the machine taken on line *a a* of Fig. 2. Fig. 2 a plan of the machine, Fig. 3 is a detail plan of 35 the central part of pan arms showing the eccentric for imparting motion to the table or annular pan, and Fig. 4 a view of discharge end of pan, while Fig. 5 is a central sectional view of part of the machine when two pans 40 are employed. Fig. 6 a detail view of the end parts of the feed and discharge ends of pans, and Fig. 7 a detail plan showing the arrangements of riffles. Figs. 8, 9 and 10 are details of the discharge end of the table 45 showing the sliding hopper and means for adjusting the height of the discharge end. Fig. 11 is a detail view showing the means provided for the radial or transverse adjustment of the table.

50 The annular pan or table A is made with an outer upstanding rim A¹, while its inner edge is for the most part flush with top of table to allow the gangue to be discharged to

the internal gutter or race B, which, at its lowermost end, is provided with a discharge 55 opening B¹.

*a*¹ is a rim on inner edge of pan stretching from free end to the gutter B. The surface of said volute-shaped pan or table A takes a helical course, that is to say, starting from 60 the discharge end A² for the saved mineral the surface gradually rises until its radial end beyond a feed hopper A³ stands higher than the surface at the discharge radial end, or in other words there is a step of some 65 inches between the terminals at the feed and discharge surface of the table. Said incline surface gradually decreases in fall towards the discharge and narrower end A² of the volute surface, while for some classes of ore 70 the table is adjusted to have a very slight upward incline at its discharge end.

The pan or table A is connected by three radial arms C¹ to a central boss C. The pan or table A is suspended by three or more 75 chains D carried by adjustable screwed hooks d supported on rubber washers d¹ seated in sockets d² formed in arms D¹ projecting from a suitable central pillar E which is firmly secured upon a gear bracket E¹, the 80 bottom part of which is in the form of a stool E²; said gear bracket E¹ has bearings for horizontal drive shaft F upon which are fast and loose belt pulleys F¹ and a bevel wheel F² which gears with a bevel pinion F³ on the 85 upper end of a vertical shaft F⁴ supported in a bearing F⁵ carried by said stool E², while secured upon the lower end of said vertical shaft F⁴ is a flanged collar G which supports an adjustable eccentric G¹ which passes 90 into a bearing C² formed in the central boss C located and secured at the center of the arms of the pan or table A, and it is by the said eccentric disk G¹ having a throw of about seven-sixteenths of an inch or thereabouts and rotating at about two hundred revolutions per minute that the gyratory or eccentric shaking motion is imparted to the table A, as it swings upon its chain or flexible suspensors D. Said eccentric G¹ is so secured 95 to the flanged collar G that its throw can be adjusted by means of such as bolts c passing through slots c¹ in the eccentric G¹, and through the collar G which is secured to the lower end of vertical shaft F⁴. 100

If so desired the eccentric may be of the 105

ball type that is it may have a spherical working surface which will admit of the free swaying of the pan.

The bearing C² may be made in the form of an open top dish in order that the eccentric G¹ may work in an oil or other lubricant, also the bearings for the drive shaft F may be of the adjustable type supported on side center pins, further the hook bolts d of the suspending chains D can be, as shown, furnished with adjusting nuts.

The volute shaped table surface A may be constructed in four or more segmental sections, each in one casting or it may be made of sheet metal with the rims and gutter secured to it, while the whole of said volute shaped surface and rim A¹ is covered with amalgamated copper plate, and further it may have curved amalgamated ripples a² on a portion of its surface.

The ore or material to be treated is fed to the table in a finely pulverized and fluid state through the hopper A³ at the high and widest end of the annular volute shaped pan or table A, said hopper A³ being perforated on its bottom and through which latter the materials pass to the table A.

A curved water spray pipe H is provided to play upon the material as it reaches the extreme outer edge of the last quarter of table A, the direction and quantity of such feed water being capable of adjustment, and when necessary other perforated jet pipes can be arranged at suitable positions to play on the material on table A. Feed water pipes H¹—H² are provided for the feed hopper A³ and the semi-circular trough K respectively.

At the discharge end of the table A is a sliding hopper I which is provided with a partition I¹. One half of said hopper I receives the valuable mineral which has been collected at or near the rim A¹ while the other half receives the seconds or material of less specific gravity and which flows over the inner surface of the discharge part A² and which material can again be put through the machine. It will be noted that the inner side of discharge end A² is flared to allow freedom for the seconds overflowing to the hopper I. As shown in Figs. 8, 9 and 10 the sliding hopper I is supported on a bracket or lug g² which is secured to the end of the gutter B, by bolts and said hopper I is held in the desired position by a spring I² which is carried on a lug x projecting up from the said bracket g². To adjust the position of hopper I the nut of bolt in lug x holding the spring I² is slackened and the tension on hopper I is thus reduced so that it can be moved transversely to the discharge end of table. The hopper is provided at each end with spouts J and J¹, the spout J carrying the valuable material to a collecting hopper J², while the spout J¹ leads the seconds to said semi-circular trough K from which the

material is again delivered on to the table A by means of a tympanum elevator K¹ which is driven by a worm gear L, receiving motion from the main drive shaft F by means of belt pulleys f and f¹. Said tympanum elevator 70 has three semi-circular tubular arms k through which the "seconds" pass to a hollow boss and from which they are delivered to table by the tapering chute k¹.

When the two pans are arranged one above another, as shown in Fig. 5, the upper pan is carried from the lower pan by three or more brackets as A⁵, while a chute A⁶ is provided between the discharge end of the upper pan and the feed end of the lower pan or the chute A⁶ may be dispensed with and the seconds only be returned from the upper pan to the lower pan so that the supply to each pan or table may be divided in place of feeding all the material to one pan and from thence 85 to the other.

To adjust the height of the discharge end of table A A, a bar g is secured to the underside of same, and said bar projects out beyond the inner edge of the table and is furnished at its outer end with a set screw g¹ which is screwed into the fixed bracket g² secured by bolts to gutter B and which supports the sliding hopper I and by screwing the said set screw g¹ up or down the discharge end of 95 table may be raised or lowered. To adjust the table bed set screws h are arranged to pass through the radial arms C¹ and bear against lugs h¹ formed on the underside of the gutter B.

To adjust the radial incline of the table A from its outer rim A¹ to the gutter B a series of angle bars e are secured to the underside of table A, and are connected by screwed adjusting rods e¹ which pass through lugs e² 105 formed both on the underside of gutter B and on the lower edge of internal rib a¹; said rods e¹ being provided with adjusting nuts e³— see Fig. 11. The height of the head or widest portion of the table A is adjusted by means of a bolt passing through a slotted bracket A⁴ secured to the radial arm C¹, said bolt being screwed into the end of table.

Having now described my invention what I claim as new and desire to secure by Letters 115 Patent is:—

1. A concentrator and amalgamator comprising a pan volute shape in plan and having a somewhat flat fall helically which gradually decreases from its feed to its discharge end and a gutter connected to the inner edge of the said pan, said gutter extending from the discharge end to a point intermediate the ends of the pan and said pan being of channel form from the end of the gutter to the feed 125 end.

2. An amalgamator or concentrator comprising a pan of volute shape in plan and having a fall helically from its feed to its discharge end, a gutter connected to the inner 130

edge of the pan, means for adjusting the height of the feed end in relation to the discharge end of the pan and means for raising or lowering the outer edge of the pan in relation to the inner edge thereof.

3. An amalgamator or concentrator comprising a pan of volute shape in plan and having a fall helically from the feed to the discharge ends, means for adjusting the height of the feed end in relation to the discharge end, adjustable means for inclining the pan radially, flexible suspending means for said pan and means for giving said pan a gyratory or eccentric motion.

4. In a concentrator and amalgamator comprising a pan of volute shape in plan and having a fall spirally from its feed to its discharge end, a gutter connected to the inner edge of said pan and means for adjusting the height of the discharge end of the pan in relation to the end of the gutter.

In testimony whereof I have signed my name to this specification in the presence of two subscribing witnesses.

JOHN ROBERT HARRISON.
